RESTAURANT ARRANGEMENT INCLUDING DINING TABLES ON SIMULATED BOATS

BACKGROUND OF INVENTION

It is well recognized that the success of a restaurant is dependent not only upon the quality of food and service, but upon the environment which is established by the physical structure, particularly the dining area. Among the desired objectives within the dining environment is a relative isolation of individual parties so as to avoid an impression of overcrowding and provide reasonable privacy of conversation, while at the same time avoiding the confinement inherent in individually partitioned facilities, such as booths. The appeal of a restaurant can be even further enhanced by an element of novelty in the dining facilities. To this end, restaurants have been proposed with underwater dining rooms (Italian Pat. No. 423,864 and U.S. Design Pat. No. 203,333), with dining tables on moving turntables (U.S. Pat. Nos. 2,689,986 and 3,091,815), in a building configured as a simulated boat (U.S. Design Pat. No. 216,009), and with facilities for each individual dining party placed on a respective railway vehicle (U.S. Pat. No. 1,377,969). Moreover, the proximity of a body of water to the dining area is frequently regarded as establishing a particularly pleasing environment as evidenced by numerous restaurants situated so as to overlook a body of water of having dining tables situated around a pool.

OBJECTS OF INVENTION

The foregoing desiderata are met by the dining room of this invention, which has among its objects the provision of a restaurant characterized by a plurality of individual dining facilities comprising simulated boats and wherein

1. a dining party is provided with an individual dining environment relatively isolated from other parties,
2. the individual dining facility is free of confining barriers,
3. diners are brought into close proximity to a body of water.

DESCRIPTION OF DRAWINGS

The foregoing, and other self-evident advantages and objects inherent in this invention will be best understood by a consideration of the ensuing specification and drawing which depicts a perspective view of a dining area constructed as a preferred embodiment of this invention.

DESCRIPTION OF INVENTION

The dining area of this invention may or may not be enclosed by walls or other barriers having an entrance 2 opening to a walkway comprising an area 3 which borders a pool 4. The pool is defined by a bottom 5 and sides 6, 7, 8 which may vary in their dimensions and configurations in accordance with the demands or preferences in particular installations. Disposed within the pool 4 are a plurality of individual dining facilities

comprising isolated platforms 9. While these platforms may be of any configuration, the illustrated embodiment comprises simulated boats which are in keeping with the water environment, and are hereinafter referred to as boats.

While each boat could float upon the water surface, the interest of safety is better met if it is made stable by directly resting on the bottom 5 or by provision of a supporting means, here illustrated as a pedestal 10 and base 11 formed integrally with the boat, or by forming the entire structure of concrete. Although other equivalent supporting structures could be employed, the pedestal is preferred in order to provide support which is not readily visible from above the surface and thus preserves the illusion that the platform is an actual boat.

Means for access are provided between each boat 9 and the walking area 3. Such means as simulated gangways or piers may be provided, or the means may comprise steps 12 extending into each boat 9 where a boat closely abuts the sides 6, 7 or 8. Each boat supports appropriate dining facilities such as a table 13 and chairs 14, and may be further decorated as by an umbrella 15. Each boat is depicted in the drawing as being of uniform size, it being obvious, however, that departures from uniformity may be taken in order to accommodate both large and small parties and that individual platforms may differ in configuration to simulate aquatic structures appropriate to their size. Thus, a large platform might take the form of a pier (not shown) or larger ships, whereas accommodations for smaller parties simulate rowboats as shown.

From the foregoing, it is evident that the dining facilities of this invention carry out the various objects set forth, the specifically described facility being set forth in the manner of example only and not in the way of limitation of the scope of this invention, which is to be determined by the following claims:

I claim:

1. A restaurant including means defining a dining area comprising a pool confined by means including a bottom and sides, at least a portion of said sides bordered by a walkway, a plurality of separate dining facilities, each said facility comprising a platform disposed within the confines of said pool in close proximity to the surface thereof and being open to the atmosphere above said surface, each said platform being limited to a size substantially smaller than said dining area and appropriate to accommodate an individual dining party thereon, means rigidly supporting said platforms from said confining means in spaced relationship to each other and thus isolated by intervening substantially unobstructed areas of said pool surface, at least one dining table disposed upon each said platform.

2. A dining facility as set forth in claim 1 wherein said individual platforms comprise simulated boats.

3. A dining facility as set forth in claim 1 including access means extending between said platforms and said walkway.
